(57) **CLAIM**

I claim the ornamental design for a helmet carabiner lock with rubber coating, as shown and described.

DESCRIPTION

FIG. 1 is a perspective side view of a helmet carabiner lock with rubber coating showing the new design; and
FIG. 2 is a left side view of the invention showing the new design; and

FIG. 3 is a front view of the invention showing the new design; and
FIG. 4 is a left side view of the invention showing the new design; and

FIG. 5 is a top view of the invention showing the new design; and
FIG. 6 is a bottom view of the invention showing the new design; and,

FIG. 7 is a rear view of the invention thereof.
